KITE-TYPE SEWER WASHER

William D. Osborn and Hubert R. Crane,
Los Angeles, Calif.

Application June 15, 1942, Serial No. 447,192

1 Claim. (Cl. 15—104.30)

This invention is a sewer or bore cleaner of what is known as the "kite" type and is kindred to the device shown in our application S. N. 227,771.

The instant invention and the tool of said patent have several features in common, and a common principle of structure in general and attention is directed to said patent for features here disclosed and not here claimed.

An object of this invention is to provide certain and new arrangements of the several structural elements whereby to facilitate manufacture of parts, their assembly and the practical operation and application of the new tool in a given bore and its traverse thereof to clean the bore and clean out detritus therein.

A purpose is to provide for the ready interchange of collapsible piston heads of the tool so that the body assembly and its carriage may be quickly adapted to bores of different sizes.

A further aim of the invention is to provide a means to quickly and effectively obtain release of the tool in instances where it may become jammed in a bore being cleaned.

The invention consists in certain advancements in this art as set forth in the ensuing disclosure and having, with the above, additional objects and advantages as hereinafter developed, and whose constructions, combinations and sub-combinations and details of means and the manner of operation will be made manifest in the following description of the herewith illustrative embodiment; it being understood that modifications, variations and adaptations may be resorted to within the scope, spirit and principle of the invention as it is more directly claimed presently herein.

Figure 1 is a longitudinal elevation, partly sectioned, of the tool as in operative adaptation.

Figure 2 is a transaxial section on line 2—2, Fig. 1.

Figure 3 is a head-end elevation of the tool.

Figure 4 is a cross-section on line 4—4, Fig. 1, omitting the rear face of the piston.

Figure 5 is a structural detail section across the axis of distended, hinged piston elements.

Figure 6 is a sectional detail of the removable, piston hinge axle assembly.

Figure 7 is a view, in longitudinal broken section, of the piston leaf carrying body element or core.

In this embodiment a stiff, tubular or other form of body element 2 is adapted to be automatically centered in a bore by longitudinally spaced, annular sets of pilot wheels 4 on trans-

verse spindles 5 in the outer ends of respective, radial, twin-part arms 6 having pivots 7 on the body member 2, whereby to allow the wheels to have a swing toward or from the member 2 to compensate for either changes in the bore size or to clear non-removable obstacles along the bore face.

The arms 6 are normally held in perpendicular, radial position to the member 2 by opposed and balanced tension springs 8 and 9 attached to outer portions of the respective arms and to anchors 10—11 at opposite sides of the relative arm pivots 7, on the member 2.

To the tail end, in this case of the member 2, there is attached by a swivel 12, a retracting cable or other appropriate means 13 for pulling back the tool in case it cannot be driven forward by a hydraulic head in the bore of a sewer S, for instance, to a desired outlet or manhole.

15 The parts just set forth constitute a form of carriage of self-centering function in a bore to be cleaned or de-sanded.

To accomplish the automatic propulsion of the tool by a hydraulic head in the sewer there is provided a means in the form of a sufficiently collapsible kite or piston which is self-distending to a normal, flat disc form. In the instant disclosure there is slidably related to, and mounted on the body member 2, a second body member 25, here called the "core" for distinction, having a stop shoulder 26 limiting axial sliding action inwardly of the core on the member 2 under the tension of suitable springs 27 anchored at 28 to the forward portion of the member 2 and attached also to the rear face of related, semi-disc plates 29—30.

These plates parts 29 and 30 are, at their diametrical edges, provided with any suitable interlocking structure, as bight straps 31 looped about a common, diametrical axle composed of aligned, radial rods 32 which are preferably removably screwed at 33 into opposite sides of the core 25. The semi-discs 29—30 form the basal support of and for a suitable, diametrically split piston packer 34 which may be of firm and flexible rubber or a suitable substitute sheet form and has abutted edges at the axle. The front (down stream) face of the piston packer 34 is armored by flat, semi-disc covers 35 rigidly secured against the packer by bolts 36 or other suitable means also securing, in the assembly, the piston parts 29—30.

The springs 27 are secured, at their forward ends, to anchors 37, on respective piston parts 29—30, at locations inwardly from the outer ends

of diametrically opposite links 38 having anchors 39 at their inner ends on the forward end of the carriage body member 2 and being distally attached at 40 to the margins of the piston parts 29-30.

Therefore, if the piston gets stuck in a bore if, then, the main body member 2 is pulled rearwardly by the retracting cable 13 the links 38 will tug on the piston leaves and tend to relatively collapse them at their hinge so that the head water being used may flow past the rim of the piston parts and wash ahead interfering detritus or sand, or the whole tool can be pulled back by the cable 13 in some instances of use.

If desired that is a set of braces 41 interposed between the body member 25 and the leaves to coat with the links 38.

The piston device is provided with a central port 18 for the free flow of water forwardly to the bore space ahead of the tool to wash downstream the detritus in the bore.

The tool may or may not be provided at its head end with a pull-in cable P attached to the core 25, which may be tubular as shown.

It will be seen that an outfit, of this invention, will include a plurality of pistons of different packer 34 sizes for use in different size bores, and any desired size piston may be quickly mounted in

place on the core member 25 by merely slipping the desired piston to place and then screwing in the interhinging rods 32 the heads 32x will center the pistons as to the axial core.

The flexible piston packer 34 is preferably of flat form as in Fig. 1, but may flex to some degree, in operation of the tool, at the rim.

What is claimed is:

A kite type sewer washer including a tubular, elongate, rear, body member having a pull back device on its rear end, a fore end body member having a stem slidable axially in the said rear member and having a pulling hitch, a pair of semi-discs forming a piston and foldably connected by a pivot device mounted diametrically on said fore member and about which the semi-discs fold in one direction as said members axially shift relatively, rigid braces pivoted at their outer ends to outer portions of said semi-discs and pivoted at their rear and inner ends to the rear body, and a set of tensioned springs connected to the rear member and to said semi-discs to concurrently contract the body members and to pull the semi-discs into a common, piston forming plane; said members having mutual position limiting stops.

WILLIAM D. OSBORN.
HUBERT R. CRANE.
